DESIGN FOR A COOKING STOVE

Anton J. Yeager, Wisconsin Rapids, Wis., assignor to Prentiss Wabers Products Co., Wisconsin Rapids, Wis., a corporation of Wisconsin

Application July 28, 1943, Serial No. 110,783

Term of patent 7 years

(Cl. D81—4)

To all whom it may concern:

Be it known that I, Anton J. Yeager, a citizen of the United States, residing at Wisconsin Rapids, in the county of Wood and State of Wisconsin, have invented a new, original, and ornamental Design for a Cooking Stove, of which the following is a specification, reference being had to the accompanying drawing, forming part thereof.

I claim:

The ornamental design for a cooking stove, substantially as shown.

ANTON J. YEAGER.
